DESIGN FOR A MUSICAL WIND INSTRUMENT

James Ross Gillie, New York, N. Y., assignor to Hal Horne, New York, N. Y.

Application September 11, 1940, Serial No. 94,941

Term of patent 14 years

To all whom it may concern:

Be it known that I, James Ross Gillie, a citizen of the United States, residing at New York city, in the county of New York and State of New York, have invented a new, original, and ornamental Design for a Musical Wind Instrument, of which the following is a specification, reference being had to the accompanying drawing, forming part thereof.

I claim:

Fig. 1 is a perspective view of the musical wind instrument, showing my design;

Fig. 2 is a top plan view; and

Fig. 3 is a front elevational view thereof.

The ornamental design for a musical wind instrument, as shown.
